UNITED STATES PATENT OFFICE

150,025

DESIGN FOR A PLAQUE

Harold J. Moran, Trenton, Stephen P. McPhillips,
Hamilton Square, and Vincent A. Mead, Trenton,
N. J., assignors to M. & M. Products Co.,
Trenton, N. J., a partnership of New Jersey

Application July 23, 1947, Serial No. 140,460

Term of patent 3½ years

(Cl. D29—23)

To all whom it may concern:

Be it known that we, Harold J. Moran, a citizen of the United States of America, residing at 64 S. Hermitage Avenue, Trenton, county of Mercer, State of New Jersey; Stephen P. McPhillips, a citizen of the United States of America, residing at Yardville Avenue, Hamilton Square, county of Mercer, State of New Jersey; and Vincent A. Mead, a citizen of the United States of America, residing at 438 Rutherford Avenue, Trenton, county of Mercer, State of New Jersey, have invented a new, original, and ornamental Design for a Plaque, of which the following is a specification, reference being had to the accompanying drawings, forming part hereof, and wherein:

Fig. 1 is a face view of the plaque showing our new design; and

Fig. 2 is a side elevation of the same.

We claim:

The ornamental design for a plaque, as shown.

HAROLD J. MORAN.
STEPHEN P. McPHILLIPS.
VINCENT A. MEAD.
